(57) **CLAIM**

The ornamental design for a watch face for providing information on hydration and other vital signs, as shown and described.

DESCRIPTION

The FIGURE is a top view of a watch face for providing information on hydration and other vital signs, showing my new design.

The broken lines on the watch face show portions of the article and form no part of the claimed design. The broken lines showing a watch and a watch band show environmental structure and form no part of the claimed design.
